OFFICE, PLLC; David W. Carrithers(57) **CLAIM**

The ornamental design for a ship sluice as shown and described.

DESCRIPTION

FIG. 1 is a perspective view of a ship sluice showing my new design;

FIG. 2 is a left side view thereof;

FIG. 3 is a right side view thereof;

FIG. 4 is a top view thereof;

FIG. 5 is a bottom view thereof;

FIG. 6 is a front end view thereof;

FIG. 7 is a rear end view thereof; and,

FIG. 8 is a perspective view including a mast, sail, tray, and pan shown in broken lines.

The broken lines showing the sluice in FIGS. 1, 4, and 8; showing the posts in FIGS. 1, 2, 3, 6, 7, and 8; showing the tray, pan, mast and sail in FIG. 8 are for the purpose of illustrating environmental subject matter and form no part of the claimed design.
